An apparatus for trimming brochures has a pair of front cutting blades and a transport apparatus for guiding the brochures to the pair of front cutting blades. For an operator-friendly changeover of the apparatus which is associated with little expenditure, in the event of a change of the distance between the front edges of the brochures and their respective setpoint cutting line, the transport apparatus can be locked at adjustable distances from the pair of front cutting blades.

APPARATUS FOR TRIMMING BROCHURES

CROSS-REFERENCE TO RELATED
APPLICATIONS

This application is a division of application Ser. No. 11/097,078, filed Apr. 1, 2005. The application also claims the priority, under 35 U.S.C. §119, of German patent application DE 10 2004 021 959.1, filed May 4, 2004. The disclosure of the prior applications is herewith incorporated by reference in its entirety.

BACKGROUND OF THE INVENTION

Field of the Invention

The invention relates to an apparatus for trimming brochures. The apparatus has a pair of front cutting blades and a transport apparatus for guiding the brochures to the pair of front cutting blades.

An apparatus of this type forms a constituent part of an assembly marketed by Brehmer Buchbindereimaschinen AG of Germany under the name Rückstich-Broschurenstrecke 750. There the apparatus has a transport system in a trimming station which comprises the pair of front cutting blades, which transport system aligns the spines of the brochures transferred to it against a stop which is positioned in such a way that the pair of front cutting blades trims the brochures along a respective setpoint cutting line. The transport system is preceded by a trimmer feed means. In order to ensure the reliable transfer of the brochures by means of the trimmer feed means to the above-mentioned transport system, in particular in the case of small formats of the brochures, it is necessary to guide the brochures as near as possible to the pair of front cutting blades by way of the trimmer feed means. The distance between the pair of front cutting blades and the trimmer feed means should be set as a function of the width of the respective strip to be cut from the brochures, what is known as the cutoff width in front trimming, in order to achieve reliable falling of cutting waste when separating a strip having a defined cutoff width from the respective brochure. The setting of the respectively required distance between the pair of front cutting blades and the trimmer feed means requires a certain amount of fitting time. For that purpose, components have to be released, displaced and fixed once more by means of tools in the above-mentioned prior art apparatus.

SUMMARY OF THE INVENTION

It is accordingly an object of the invention to provide an apparatus for trimming brochures which overcomes the above-mentioned disadvantages of the heretofore-known devices and methods of this general type and wherein the apparatus is configured such that it requires as short a fitting time as possible for the changeover to a job for which the above-mentioned cutoff width is changed.

With the foregoing and other objects in view there is provided, in accordance with the invention, an apparatus for trimming brochures, includes a pair of front cutting blades. A transport apparatus guides the brochures to the pair of front cutting blades in a transport direction. A displacement device has at least one eccentric disk for positioning the transport apparatus at adjustable distances from the front pair of cutting blades. A locking device locks the transport apparatus at the adjustable distances from the pair of front cutting blades.

2

In other words, the objects of the invention are satisfied by rendering it possible to lock the transport apparatus at adjustable distances from the pair of front cutting blades.

If a relatively wide gap is to be set between the pair of front cutting blades and the transport apparatus in the case of a relatively large cutoff width, that is to say a relatively large width for the strips to be separated from the brochures, a development in this respect proves to be advantageous in that the transport apparatus has a ramp which raises that end of the transport apparatus which faces the pair of front cutting blades when the transport apparatus is moved away from the pair of front cutting blades.

Other features which are considered as characteristic for the invention are set forth in the appended claims.

Although the invention is illustrated and described herein as embodied in an apparatus for trimming brochures, it is nevertheless not intended to be limited to the details shown, since various modifications and structural changes may be made therein without departing from the spirit of the invention and within the scope and range of equivalents of the claims.

The construction and method of operation of the invention, however, together with additional objects and advantages thereof will be best understood from the following description of specific embodiments when read in connection with the accompanying drawings.

BRIEF DESCRIPTION OF THE DRAWINGS

FIG. 1 is a diagrammatic side view of a section of a trimmer for trimming brochures and a transport apparatus for guiding the brochures to a pair of front cutting blades of the trimmer;

FIG. 2 is a perspective detail illustrating a first embodiment of the connection of the transport apparatus to the trimmer;

FIG. 3 is a perspective view showing the embodiment of FIG. 2 from a different viewing angle; and

FIG. 4 is a perspective view of a second embodiment of the connection between the transport apparatus and the trimmer.

DESCRIPTION OF THE PREFERRED
EMBODIMENTS

Referring now to the figures of the drawing in detail and first, particularly, to FIG. 1 thereof, there is shown an apparatus for trimming brochures 1 according to the invention. The apparatus comprises a pair of front cutting blades 5 formed from a lower blade 3 which is arranged fixedly in terms of position on a trimmer frame 2 and an upper blade 4 which interacts with the latter, and a transport apparatus 6 for guiding the brochures 1 to the pair of front cutting blades 5.

In the present exemplary embodiment, the transport apparatus 6 carries the brochures 1 by way of a roller track 7 and the transport is carried out by way of drivers 8 which are disposed on non-illustrated endless chains that circulate during operation.

An end of the transport apparatus 6 which faces away from the trimmer frame 2 rests on a stationary support 9, for example in the form of a freely rotatable roller, on which the transport apparatus 6 can roll when it is being set to different distances A from the pair of front cutting blades 5.

Referring now to FIGS. 2 and 3, an adjusting shaft 10 which is supported by side parts 2.1 and 2.2 of the trimmer frame 2 is provided to support that end of the transport apparatus 6 which faces the trimmer frame 2. A respective side cheek 6.1 and 6.2 of the transport apparatus 6 is positioned on this adjusting shaft 10, or more accurately on a respective

end-side collar **10.1** of the latter, to be precise with a supporting face **6.6** formed on a respective side cheek **6.1** and **6.2**.

In order to set various distances **A** between the transport apparatus **6** and the pair of front cutting blades **5**, an eccentric disk **10.2** which is fixed in terms of rotation with respect to the adjusting shaft **10** is provided on a respective end of the adjusting shaft **10**. Each respective eccentric disk **10.2** engages in a slotted guide **6.3** and **6.4** provided on a respective side cheek **6.1** and **6.2**. Each of the slotted guides **6.3** and **6.4** has an extent in the longitudinal direction of the transport apparatus **6** which corresponds to the diameter of the eccentric disks **10.2**.

A front and rear limit (with regard to the transport direction according to arrow **T** in FIG. 1) for each of the slotted guides **6.3** and **6.4** is formed in each case by a sliding rail **6.5** which is in contact with the corresponding eccentric disk **10.2** and is fastened to the respective side cheek **6.1** and **6.2** of the transport apparatus **6**.

An adjusting lever **10.3** is connected fixedly in terms of rotation to the adjusting shaft **10** at one end of the latter. When the adjusting shaft **10** is rotated by means of said adjusting lever **10.3**, the eccentric disks **10.2**, being in contact with the sliding rails **6.5**, displace the transport apparatus **6** in one or the opposite displacement direction, depending on the rotational direction.

The supporting face **6.6** which represents a respective upper limit of the respective slotted guide **6.3** and **6.4** is preferably configured in the form of a ramp **6.7** which falls away in the direction toward the trimmer frame **2** and to this extent raises that end of the transport apparatus **6** which faces the pair of front cutting blades **5** when the transport apparatus **6** is moved away from the pair of front cutting blades **5**.

In this way, sagging of the leading edges of the brochures is taken into consideration in an advantageous way in the case of a large cutoff width.

FIG. 4 illustrates an alternative to the displacement mechanism illustrated in FIGS. 2 and 3. Here, given an otherwise identical configuration of the trimmer frame **2** and the transport apparatus **6**, the eccentric disks **10.2** are replaced, in functional terms, by crown gears **10.5** and the sliding rails **6.5** of a respective slotted guide **6.3** and **6.4** are each replaced by a rack **10.6** which is oriented in the displacement direction and meshes with a respectively assigned crown gear **10.5**.

The transport apparatus **6** is displaced in order to set its distance **A** from the pair of front cutting blades **5** in the same way as in the mechanism which operates with the eccentric disks **10.2**, by rotating the adjusting shaft **10** by means of the adjusting lever **10.3** which is arranged on it fixedly in terms of rotation.

In both alternatives, the same locking means are provided, by means of which the transport apparatus **6** can be locked at adjustable distances **A** from the pair of front cutting blades **5**. These locking means comprise a thread cut onto an end section and a clamping lever **10.4** provided with a nut thread which interacts with the other thread, at the same end of the adjusting shaft **10** at which the adjusting lever **10.3** is arranged. The rotationally fixed connection of the adjusting lever **10.3** to the adjusting shaft **10** is configured in such a way that the adjusting lever **10.3** is merely pushed onto the adjusting shaft, that is to say is not fixed on the adjusting shaft **10** in the axial direction. For example, the adjusting lever **10.3** has a hub **10.3'** which is connected to the adjusting shaft **10** via a key and can be pressed against the directly adjacent side cheek **6.1** or **6.2** (cf. FIG. 4), with the result that the hub **10.3'** is pressed against the abovementioned directly adjacent side

cheek **6.1** or **6.2** (here, against the side cheek **6.1**) by screwing the clamping lever **10.4** onto the thread of the adjusting shaft **10**, and therefore the rotational position of the adjusting shaft **10** and thus the position of the transport apparatus **6** assumed in the process are fixed.

Both the displacement mechanism which operates with the eccentric disks **10.2** and the sliding rails **6.5** and the displacement mechanism which operates with the crown gears **10.5** and the racks **10.6** obviously permit the infinitely variable adjustment of the distance **A** between the transport apparatus **6** and the pair of front cutting blades **5**.

I claim:

1. An apparatus for trimming brochures, comprising:
a pair of front cutting blades;
a transport apparatus for guiding the brochures to said pair of front cutting blades in a transport direction, said transport device having a slotted guide;
a displacement device having at least one eccentric disk engaging in said slotted guide for positioning said transport apparatus at adjustable distances from said front pair of cutting blades;
said transport apparatus including a ramp for sliding across a positionally fixed element to raise an end of said transport apparatus facing said pair of front cutting blades when said transport apparatus is moved away from said pair of front cutting blades; and
a locking device for locking said transport apparatus in a given locked position at any of a plurality of adjustable distances from said pair of front cutting blades.
2. The apparatus according to claim 1, wherein said displacement device is configured to adjust the distances in an infinitely variable manner.
3. The apparatus according to claim 1, wherein said transport apparatus has circulating drivers configured to transport individual ones of the brochures along said transport apparatus.
4. The apparatus according to claim 1, wherein said at least one eccentric disk is a pair of eccentric disks spaced apart from one another.
5. The apparatus according to claim 4, wherein said displacement device has an adjusting shaft, said eccentric disks are disposed on said adjusting shaft.
6. The apparatus according to claim 5, wherein said eccentric disks are fixed in terms of rotation with respect of said adjusting shaft.
7. An apparatus for trimming brochures, comprising:
a pair of front cutting blades;
a transport apparatus for guiding the brochures to said pair of front cutting blades in a transport direction, said transport device having a slotted guide;
a displacement device having at least one eccentric disk engaging in said slotted guide for positioning said transport apparatus at adjustable distances from said front pair of cutting blades;
said transport apparatus including a ramp for sliding across a positionally fixed element to raise an end of said transport apparatus facing said pair of front cutting blades when said transport apparatus is moved away from said pair of front cutting blades; and
a locking device for locking said transport apparatus in a given locked position at any of a plurality of adjustable distances in said transport direction and adjustable heights from said pair of front cutting blades.
